LIFTING-TRUCK.

1,167,564.

Specification of Letters Patent. Patented Jan. 11, 1916.

Application filed February 2, 1915. Serial No. 5,628.

To all whom it may concern:

Be it known that I, WILLIAM F. IRRGANG, a citizen of the United States of America, residing at Windsor Locks, in the county of 5 Hartford, State of Connecticut, have invented certain new and useful Improvements in Lifting-Trucks, of which the following is a specification.

This invention relates particularly to improvements in that type of truck termed a "lifting" or "elevating" truck. This type of truck has been known for a long time and involves in its construction a part which is vertically movable with respect to the rest 10 of the truck. Mechanically, it is a jack mechanism mounted on wheels so that it may be used both as a "jack" and truck in various systems of lifting, holding, transferring, and depositing loads of material to save loading 15 and unloading in the ordinary sense.

The object of this invention is to provide an improved mechanical means in such a truck for lifting the load, which is operable by manipulating the handle.

Another object is to provide an improved arrangement of the handle and handle-operated lifting means with respect to the truck.

Another object is to provide an improved means for holding the lifting platform of 30 the truck in lifted position and releasing it when desired, which means is controlled and actuated by movement of the handle-operated lifting means.

Other objects are to provide in a lifting 35 truck generally improved mechanical structure, improved arrangements for the structure, and improved modes of actuating the structure as will be defined in the annexed claims.

For the purpose of illustrating one preferred form or embodiment and certain specific modifications of the invention, the drawings and following detailed descriptions thereof are used.

In the accompanying drawings: Figure 45 1 is a top plan view of the truck with the platform shown in elevated position; Fig. 2 is a side elevational view thereof; Fig. 3 is a fragmentary sectional elevation taken on the line 3—3 of Fig. 1 and looking in the direction of the arrows; Fig. 4 is a partial side elevational view of the truck with the platform shown in lowered position; Fig. 5 is a sectional elevation of the operating

mechanism connected with the handle; Fig. 55 6 is a cross-sectional view taken on the line 6—6 of Fig. 2 and looking in the direction of the arrow; Figs. 7, 8, and 9 are views similar to Fig. 3, showing various steps in the raising and lowering of the truck platform; Fig. 10 is a sectional view showing a part of the mechanism for holding the platform in lifted position; Fig. 11 is a modification of the operating mechanism connected with the handle; Fig. 12 is a view similar to Fig. 10 showing a modification; Fig. 13 is a detail plan view showing the preferred manner of positioning the power applying means to the platform; Fig. 14 is a sectional view taken on line 14—14 of Fig. 13; Fig. 15 is a view similar to Fig. 4, showing a preferred form of the handle-operated means for shifting the movable platform of the truck; Fig. 16 is a central longitudinal sectional view of the means shown in Fig. 15; Fig. 17 is a view similar to Fig. 16, showing the parts in another position; Fig. 18 is a transverse sectional view taken on the line 18—18 of Fig. 15 and looking in the direction of the arrows; Fig. 19 is a cross sectional view taken similarly to Fig. 6 showing a modification of the platform lifting devices, and Fig. 20 is a partial side elevation of the truck showing a modification in the arrangement of the platform lifting devices. 85

Referring to the drawings in detail and particularly to Figs. 1 and 2, the frame of the truck comprises a pair of spaced reach bars 1, rigidly joined at their forward ends by a casting 4 in which a fifth wheel device, 90 including the front wheel 5, is mounted. The rear wheels 2 are mounted on an axle 2' which is secured in the reach bars 1. The liftable platform of the truck 3 is conveniently made up of angle iron sections, as clearly shown in Figs. 1 and 2. Lifting devices are interposed between the platform 3 and the bars 1, and these devices, when the platform is moved longitudinally by means to be described, are operable to lift the platform. These devices, in the embodiment of my invention illustrated, are four in number and are preferably applied adjacent the four corners of the truck platform. A description of one of these lifting devices will suffice 95 for all.

Consider Figs. 3 and 6; fixed to the under-side of the platform 3 and depending there-

from is a rack 8, which is arranged with the pitch line in an inclined position. Adjacent the rack 8 and integral therewith is a cam 8' having a surface corresponding with the pitch line of the rack. Pivotedly mounted in a bearing at 6 in the frame 1 is an irregularly shaped or cam gear 7 which has a cam surface 7' integral therewith and corresponding to the pitch line of the gear. The gear 7 and rack 8 intermesh, and the cam surfaces 7' and 8' engage one another to support the platform 3. When the platform 3 is moved longitudinally in a rearward direction, the racks 8 will turn the gears 7, and the mechanism described will raise the platform 3 with respect to the frame in an obvious manner. The positions of the lifting devices may be varied according to the type of platform used. For example, if one of large area is desired, the pivot connections 6 with the frame 1 for the rear gears 7 may be placed back of the axle 2' as clearly shown in Fig. 20. The tendency for the platform to tip when carrying a high load will be thus largely obviated by a proper positioning of the lifting devices.

If desired the racks 8 and gears 7 may be separated from the cams as shown in Fig. 19. In this figure a gear 70 and rack 71 are arranged centrally of the frame and operate a cam rod 72 with cams 73 on the end which engage cam surfaces 74 secured to the platform 3. The construction in Fig. 19 is otherwise similar to that shown in Fig. 6 and already described. In other words, the specific positions shown for the lifting devices and the relative positions of the cams, gears, and racks are of secondary importance.

Integrally formed with the rack 8 of each elevating device is a depending web 9, shaped clearly shown in Fig. 2. This web extends downwardly closely adjacent one side of the gear 7, and the latter is positioned laterally by this web and the reach bar 1, as clearly shown in Fig. 6. Formed in the web 9 is a curved slot 11 and fixed in the gear 7 or integral therewith is a pin 10 which projects outwardly from the gear and rides in the slot 11. The web 9 and pin 10 co-operate to prevent the platform 3 from tipping or being lifted bodily from the frame 1 and the cam surfaces 7' and gears 7 upon which it rests. In other words, each elevating device has embodied therein and as a part thereof means to prevent the tipping of the platform with respect to the frame which might otherwise occur with unevenly distributed loads.

The mechanism for moving the platform 3 longitudinally with relation to the frame 1 to operate the platform lifting devices will now be described. Fixed to the swivel support for the front wheel 5 is a member 12 which has two upstanding webs arranged in parallel and spaced relation. Between these

spaced webs is a gear 14 which is rigidly secured to the truck handle 15. This gear 14 has an opening 18 extending transversely therethrough, which, as clearly shown in Fig. 5, comprises two circular holes joined by a constricted opening. Fixed in the two webs of the member 12 and extending through the opening 18 is a pin 13. The latter has one side 13' slotted off, as shown in Fig. 5, whereby it may pass, as the gear 75 is moved up and down, from one circular portion to the other circular portion of the opening 18, through the constricted portion thereof. It is to be noted that the gear is freely rotatable, when the pin 13 is in either of the circular portions and that, in order to pass from one circular portion to the other of slot 18, the gear and handle must be positioned as shown in Fig. 5. When the gear 14 is so positioned, ears 16 on the handle 15 engage abutments 17 on the member 12. Slidably mounted in the base of the member 12 is a rack 20 which has a roll 25 pivotally mounted at 24 in one end thereof.

Fixed to the forward end of the platform 3 is a casting 26 (see Figs. 1 to 3) which has a curved surface 27 forwardly inclined. The roll 25 is adapted to engage the face of casting 26 to shift the platform 3 longitudinally with respect to the frame 1, as when the rack 20 is forced backwardly as the handle 15 is swung downwardly to operate the gear 14. Pivotedly mounted at 22 on the inner sides of the upstanding webs of the member 12 is a bail member 21. The latter has forward extensions which are engageable by hubs 19 integral with the gear 14. This bail member also has a rear U-shaped portion, which extends transversely across the rack 20 and is adapted, when the parts are in the relative positions shown in Fig. 2, to engage in a notch 23 in the rack to lock the latter to the member 12. By locking the rack, as described, the insertion of the gear 14 in correct meshing relation with the rack 20 is insured after each removal of the gear therefrom. It is to be noted that, as the gear 14 is lowered to engage the rack, the hubs 19 bear upon the forward extensions of the bail member 21 and lift the same from the notch 23. These hubs 19, substantially circular in shape, also act to hold the bail member 21 away from the rack 20 while the latter is being reciprocated by the gear 14. The gear 14, rack 20, and member 12 comprising the primary means for shifting the platform, are laterally movable by and move with the handle 15 as well as the front wheel 5.

The curved surface 27, arranged as shown, permits the platform to be moved by the rack 20 when the handle 15 and wheel 5 are in various angular positions. However, the proper and best mechanical position and arrangement for moving the platform by 130

the handle and mechanism described is that shown in Fig. 4. In this arrangement, the handle, when pulled forwardly, operates through the gear 14 to force rack 20 in the direct line of the horizontal movement of the platform. Thus, all the force applied is used to the best mechanical advantage. If the handle and wheel 5 is swung around at an angle before the elevating operation, then the force applied is split into components one only of which does the work while the other tends to cramp the platform sidewise with respect to the truck frame. Therefore, the preferable arrangement is to provide on the surface 27 a central downwardly pointed wedge 27' such as shown in Figs. 13 and 14. This wedge will require the proper positioning of the handle in the central and vertical longitudinal plane of the truck during the lifting operation of the platform.

The means for holding the platform in its lifted position and for controlling the same to permit the lowering of the platform 3 will now be described. Each reach bar 1, immediately below the forward end of the platform 3, is provided with a hump 43, as shown in Figs. 2 and 3 having a rearwardly inclined surface 39. Slightly to the rear of this hump 43 and on the outermost side of each bar 1, is an upstanding web 42. Between the two webs 42 and extending transversely across the truck is a shaft 31, which bears the actuating devices for controlling the holding means. The holding devices, one at each side of the truck, are arranged in spaced relation immediately adjacent the side bars 1, as shown in Fig. 1, and one set only of these devices will be described. The controlling means for the actuating devices are positioned centrally of the truck or shaft 31.

Referring particularly to Fig. 8, 28 represents a cylindrical bolt, which is loosely mounted in the casting 26. This bolt is arranged in an inclined position parallel with the surface 39 of the hump 43 and is adapted to engage or lie back of the surface 39 to hold the platform in its elevated position, as shown in Fig. 3. Adjacent the inner edge of the side frame 1 is a lever 37 which is pinned to the shaft 31. This lever has an inwardly extending offset portion 40, which directly underlies the bolt 28, and is movable close to the surface 39 (see Fig. 10). In this portion 40 is a spring actuated ball 41, which is arranged to engage either of two recesses formed in the surface 39 to hold the lever 37 in either of the positions shown in Fig. 7 or Fig. 10. The portion 40 of this lever always supports the bolt 28 and, when raised by means to be described to the position shown in Fig. 7, permits the bolt 28 to pass over the

hump 43 and allows the platform 3 to be lowered.

Fixed to the shaft 31 and arranged centrally between the two levers 37, is a member 32 which has short arms extending above 70 and below the shaft. Pivotal mounted at 29 in ears formed on the casting 26 is a pawl 30, which is normally held by gravity in the position shown in Fig. 3. The rear end of the pawl 30 is arranged to engage 75 with the upper arm of the member 32, when the platform 3 is elevated slightly beyond the position shown in Fig. 3, to turn the shaft 31 and levers 37, whereby the bolts may be raised by the movement of the offset 80 portions 40 of said levers to lower the platform. Loosely mounted on the shaft 31 is a lever, hereinafter called the pawl-tripping lever, which has a forward flat extension 34 and a rearward extension 33. The central 85 portion of this lever is cut away to form an opening therein to receive the member 32, and the latter is positioned on the shaft 31 by this member 32. The rearward extension 33 of the pawl-tripping lever is heavier 90 than the forward extension and tends at all times to force a projection 38 against the lower arm of the member 32. The forward extension 34 directly underlies the pawl 30 when the platform is lowered, and is inclined at an angle substantially the same as the downward path of the platform 3 as indicated by the dot and dash line in Fig. 8. To the rear of this inclined portion 34 is a semi-circular depression 49 which is 100 adapted to coact with the pawl 30 in a manner to be described.

The levers 37, after having been moved to the position shown in Fig. 7 to permit the platform to be lowered, must be restored to the position shown in Figs. 3 and 10 to allow the bolts 28 to again move into position to hold the platform on its next upward movement. This is accomplished by the lower edge of the angle iron 3', 110 which lies transversely across the levers 37 and on a downward movement of the platform 3, engages these levers and moves them to the position shown in Fig. 8.

In lifting the platform by the means described, the operator naturally raises the platform somewhat beyond the point necessary to permit the bolts 28 to engage back of and against the surface 39 and allows the platform to drop back until the bolt 120 engages this surface. With the pawl 30 in the position shown in Fig. 8, there is a possibility that, when the platform is elevated as just described, the pawl 30 might engage the member 32 and move the levers 125 37 to bolt tripping position. The function of the loosely mounted lever 33-34 is to prevent such a condition by temporarily removing the pawl 30 from its normal position shown in Figs. 3, 7 and 8. Referring 130

to Fig. 8, it will be seen that as the platform 3 is moved upwardly the rearward end of the pawl 30 will catch under the forward end of the inclined portion 34 and the pawl 5 will be turned to the position shown in Fig. 9. Thereafter, the end of the pawl 30 will drag on the inclined portion 34 during the upward passage of the platform and the heavy portion 33 will hold the end 34 10 against the pawl 30 in the position shown. After the platform has been moved slightly beyond the position necessary to permit locking by the bolt 28, the pawl will ride off the inclined portion 34, and the levers 33 and 34 will rise so that the end of the pawl 30 is lodged in the recess 49. As the platform is allowed to drop back to bring the bolt 28 against the surface 39, the end 20 of the pawl 30 strikes against the forward end of the recess 49, and the pawl is forced back to its normal position, as shown in Fig. 3. This arrangement of the parts enables the operator to lower the handle to set the holding bolts, and these bolts cannot 25 be tripped to permit the lowering of the platform until the handle has been raised and again lowered. Thus, the important requirement of a volitional act on the part of the operator to lower the platform is obtained, and the latter will not be accidentally lowered when a heavy load is to 30 be carried.

Fig. 11 shows a modified form of the handle operated mechanism. The rack 20 is 35 slidable in the base of the member 12 as heretofore, but the gear 46 is permanently mounted on a pin 47 and arranged to be always in mesh with the teeth of the rack. The handle 15' is forked over the gear 46 40 and is loosely mounted on the pin 47 within the spaced upstanding webs 12'. Within the handle 15' is a slider rod 44, the end of which is arranged to engage a notch 45 in the gear 46, whereby the latter may be 45 turned as desired. When the rod 44 is disengaged from slot 45, it may move on pin 47 without moving the gear 46.

Fig. 12 illustrates a preferred form of the bolt tripping levers 37. In this modification, the offset portion 40 heretofore described is replaced by a segmental extension 48 in which the spring pressed ball 41 is mounted as heretofore described. By means of this construction, all possibility 55 of the ball 41 dropping out of the lever on account of an excessive upward movement thereof is eliminated.

The types of mechanism for shifting the platform 3 longitudinally, which have been 60 described in connection with Figs. 1 to 14, may be desirable for certain purposes. The type of mechanism, which is at present preferred, however, is shown in Figs. 15 to 18, inclusive, and will now be described.

A gear 53 is loosely mounted on a shaft 47, which is secured in the spaced upstanding webs 12', in a manner similar to that shown in Fig. 11. The handle 15 is forked, as clearly shown in Fig. 18, and has two 70 substantially circular spaced members 51 depending therefrom, which are loosely mounted on shaft 47 between the webs 12' and the gear 53. The rack 20 is slidably mounted between the webs 12' and is always in mesh with the gear 53. Formed integrally with the rack 20 on either side thereof are spaced rails 50, which directly underlie and engage the members 51 on the handle 15. The rails 50 and members 51 80 are preferably made to correspond with the pitch lines of the rack 20 and gear 53. A pair of rolls 52, rotatably mounted on the inner sides of the webs 12' also bear on the rails 50, and in coöperation with the members 51, serve to prevent the rack 20 from lifting when a load on the platform 3 is 85 being elevated. A spring 56, located within a recess in the underside of the rack 20, as shown in Figs. 16 and 17, normally retains the rack in the retracted position 90 shown in the figures.

It will be seen that, when the handle 15 is pulled downwardly from the position shown in Fig. 16, an abutment 54 on the handle will engage an abutment 55 on the gear, whereby the latter may be turned to force the rack 20 rearwardly. The roll 25 on the rack engages, as described, in connection with Figs. 13 and 14, a wedge 27' 100 which is centrally disposed on the platform 3. This wedge 27' is an integral part of a bracket 57, which curves forwardly and upwardly as shown. The end of the bracket 57 is adapted to engage the handle 15, as 105 shown in the Figs. 15 and 16, when the platform 3 is in lowered position. When the platform is in lifted position, this same bracket 57 is arranged to engage a lug 58, which extends rearwardly from and is integral with the handle 15. The bracket 57, therefore, acts to prevent the handle 15 110 from tipping rearwardly against any high load, which may be on the platform 3.

From an inspection of Figs. 16 and 18, 115 it will be noticed that the webs 12' are secured by the bolts shown to the swivel plate of the forward wheel 5, and, therefore, the webs 12', rack 20, and gear 53, comprising the handle-operated mechanism, are arranged to turn as the wheel and handle turn. Moreover, a portion of the gear 53 (as seen in Fig. 16) is cut away at the root line of the teeth. Thus, when the cross-bar 15' of the handle is turned through substantially 120 180 degrees to bring the parts in the relative positions shown in Fig. 17, the handle 15 is free to turn on the shaft 47 without turning the gear. Lugs 59 are provided on the handle 15, which are arranged to engage 125 130

either of the surfaces 60 to prevent the handle from dropping to the floor, when the rack is either in position to actuate the lifting mechanism or in reversed position, as 5 shown in Figs. 16 and 17, respectively.

The general operation of the type of truck, shown in Figs. 1 to 14, inclusive, is as follows: Assuming the platform 3 to be in elevated position, as shown in Figs. 1 10 and 3, to lower the platform, the operator first swings the handle 15 upwardly until the ear 16 engages the abutment 17. The gear 14 may then be lowered into mesh with the rack 20, and the bail 21 is simultaneously unlocked as already described. A 15 downward movement of the handle 15 will now move the rack 20 rearwardly until the roll 25 engages the curved surface 27. The forward inclination of this surface as the 20 rack moves rearwardly holds the latter on its support or anti-friction rolls can be used for this purpose as shown in Figs. 15, 16 and 17. The platform is thus moved rearwardly as described a sufficient distance to 25 cause the pawl 30 to engage the member 32 to turn the levers 37 upwardly. The bolts 28 are then lifted to a position to permit a free downward passage of the platform 3, the bolts riding freely on the forward inclined surface of the hump 43. As the platform is eased downwardly by the handle 15, the lower edge of the angle iron 3' acts to force the levers 37 downwardly and again to the position shown in Fig. 3. The gear 30 may be lifted so that the pin 13 rides in the lower circular portion of the opening 18, wherein it may move with the handle and not move the rack 20 which is held by bail 21 in position to be again moved. To 35 again elevate the truck, the handle 15 is operated as previously described to force the roll 25 against the surface 27 and the platform is moved rearwardly, whereby the cams 7 and 8 co-act to lift the platform. 40 On the upward passage of the platform, the pawl 30 is engaged by the lever 34 as described to prevent its engagement with the member 32. As the bolt 28 rides upwardly on the hump 43, it finally drops over the 45 crest thereof upon the upper surface of the portion 40. Then, when the platform is allowed to drop back, the bolt 28 engages the surface 39 to hold the platform in elevated position, and the pawl 30 is restored as heretofore described. The handle can, therefore, be used to manipulate the truck with the platform lifted or not as desired, and the handle-operated means for lifting or 50 lowering the platform is carried with the handle and is always in position to readily coöperate therewith for the desired operations. It is to be particularly noted that the handle after being lowered to lift the platform must be raised and again lowered 55 before the holding means can be positioned

to allow the platform to be lowered. This is a safety feature of considerable importance and acts to insure the proper and careful operation of the truck.

The general operation of the truck, using the preferred form of platform-shifting means shown in Figs. 15 to 18, inclusive, is as follows: Assuming the truck platform to be in lowered position and the rack, gear, and handle turned laterally by movement of the latter to the position shown in Fig. 16, to raise the platform, the handle 15 is pulled downwardly and the abutment 54 on the handle engages with the abutment 55 on the gear 53 to turn the latter. The gear forces the rack rearwardly against the small force due to the tension of spring 56 to engage the wedge 27' and force the platform 3 rearwardly, as heretofore described. The platform operated lifting mechanism and locking devices operate as formerly and the platform is lowered in a manner identical with that already described. When the platform 3 is in either its lowered or raised position and it is desired to draw the truck, the cross-bar 15' is turned 180 degrees to reverse the rack 20 and bring the parts into the relative positions shown in Fig. 17. When the parts are so positioned, the handle 15 may move in any direction and carry with it the handle-operated mechanism except that a downward movement of the handle will not operate to force the rack 20 longitudinally. When the platform is in lifted position, it is not necessary to turn the handle, gear, and rack through 180 degrees for the mutilated part of the gear permits movement of the handle without operation of the rack. It is also to be noted that the bracket 57 and lug 58 act as a stop to limit the movement of the handle in one direction and the lugs 59 and surfaces 60 act as stops to limit movement in the other direction.

The invention with certain preferred features and specific modifications has been described in detail, but the invention is more truly defined in the annexed claims than by specific examples thereof chosen for purposes of illustration.

What I claim is—

1. A lifting truck, comprising, a liftable frame supported on wheels, lifting devices operable to lift said frame, means to hold the frame lifted, mechanism to trip said means and controlling devices rendered effective by the movement of the frame to render said mechanism inoperable until said means is set to hold the frame and thereafter render it operable.

2. A lifting truck, comprising, a frame 125 mounted on wheels, a platform, devices operable on longitudinal movement of the platform to lift the latter, a rack and gear supported on the frame independently of the platform operable to move the latter 130

longitudinally and adapted to be completely separated from the platform, a truck handle constructed and arranged to turn the gear for operating the rack, said handle, gear, and rack being mounted to turn laterally as a unit.

3. A truck, comprising, a platform, devices operated by the movement of the platform to lift the latter, a truck frame on 10 wheels to support said elements, a handle operated mechanism on the frame operable when properly positioned by the operator to engage and move the platform by one downward sweep of the handle and to disengage 15 the platform by each upward sweep of the handle.

4. A truck, comprising, a platform, a handle, devices operated by the platform to lift the latter, mechanism structurally independent of the platform and movable in one direction to move the latter by abutment therewith to operate said devices and movable in the opposite direction out of contact with the platform, and a catch to hold the 25 platform lifted, said independent mechanism being movable with and by the handle.

5. A truck, comprising, a handle, a platform, devices operated by the platform to lift the latter, mechanism structurally independent of the platform and movable in one direction to move the latter by abutment therewith to operate said devices and movable in the opposite direction out of contact with the platform, a catch to hold the 35 platform lifted, said independent mechanism being movable with and by the handle, and means to trip said catch actuated by the movement of the platform.

6. A truck, comprising, a wheeled frame, a handle, a platform, lifting devices operable by and on longitudinal movement of the platform, means to cause said longitudinal movement, comprising, a slideable bar on the frame, means engageable with the 45 handle to slide said bar back and forth into and out of operable contact with the platform.

7. A truck, comprising, a wheeled frame, a steering handle therefor connected with one wheel to steer the truck, a power multiplying device connected to and movable with the handle, comprising, a laterally slideable rack, a gear in mesh therewith said gear and handle being constructed and arranged 55 to permit up and down swinging of the handle with or without the gear, a platform, devices operated by the movement thereof to lift the platform, all constructed and arranged so that the movement of the handle causes the rack to engage and move the platform.

8. In a lifting truck, a supporting wheeled frame, a platform to lift loads, means located between the platform and frame operable by a longitudinal movement of the plat-

form to lift the latter, a releasable catch device to hold the platform lifted, comprising, a downwardly movable catch member in the platform, an abutment on the frame having one surface on which the catch rides as the platform is lifted and a shoulder back of which the catch member falls when in proper vertical alinement, a trip device, actuating means therefor carried by the platform, setting mechanism for the trip 75 actuating means operable on the upward movement of the platform to prevent the operation of the trip device and operable on the proper setting of the catch to place the actuating means in position to trip the catch 80 on further movement of the platform above its normal lifted position.

9. In a lifting truck, a wheeled frame, a platform, lifting devices arranged at the several supporting points between the frame 85 and platform, each comprising, an inclined cam on one and a pivoted cam on the other, the former having a rack with its pitch line corresponding to the cam surface and the latter a cam gear in mesh with the rack with its pitch line corresponding to its cam surface, and one cam provided with a web overlapping at all times the other cam, a pin in the other cam extending through a slot in the web, said slot being cut to correspond 95 with the path of the pin as the cams move relatively one to the other, and means cooperating with said web to hold the cams in proper relative position at all times.

10. A lifting truck having, in combination, a wheeled frame, a platform, devices operable to lift the platform from the frame, a handle, mechanism operable by the handle to actuate said devices, comprising, a power multiplying means swiveled on the frame 100 and connected to the handle, said means completely rotatable by the latter on a vertical axis and movable into one position in which a downward movement of the handle will cause the operation of the devices and into another position in which the handle may swing up and down and sidewise.

11. A lifting truck, comprising, a wheeled frame, a platform thereon, lifting devices for the platform operable by longitudinal movement of the latter, a steering wheel swiveled at the front of the frame and arranged for complete rotation on a vertical axis, a handle mounted to turn on a horizontal axis and connected to said wheel, a power multiplying device arranged to turn with the handle and wheel on the vertical axis aforesaid and including a rack horizontally movable to actuate the platform, a mutilated gear in mesh therewith mounted on the horizontal axis aforesaid, a part connected with the handle movable freely around the mutilated portion of the gear but alternately engageable with the end teeth thereof, all constructed and arranged so that 115 120 125 130

the handle may be positioned to swing up and down with or without the gear.

12. A lifting truck, comprising, a wheeled frame, a liftable platform thereon, means to lift said platform, power multiplying mechanism, comprising a truck handle mounted on the frame to swing on and to completely revolve about a vertical axis, a handle-operated element arranged to actuate said means, 10 said element being arranged for actuating said means by a downward swing of the handle when in one position and turnable with the handle on its vertical axis into another position to render said element inoperative 15 able on a downward swing of the handle.

13. A lifting truck, comprising, a wheeled frame, a steering wheel therefor connected to a fifth wheel member and mounted in the frame to turn on the vertical axis of the fifth 20 wheel member, a handle, gear, and rack operably connected and comprising a power multiplying device, all mounted on said member to turn therewith, a platform on the frame, lifting and controlling devices 25 actuated by movement of the rack to raise and lower the platform, all constructed and arranged so that the power multiplying device is operable by an up and down movement of the handle when the latter is turned 30 to position the rack for operation and is rendered inoperative when turned to bring the rack out of operative position.

14. A lifting truck, comprising, a wheeled frame, a steering wheel mounted on a swiveled fifth wheel member at the front thereof, a handle pivoted horizontally on said fifth wheel member, a gear mounted to turn on the horizontal axis of the handle, a rack in mesh with said gear mounted to slide horizontally on said fifth wheel member and turn therewith, a spring between the fifth wheel member and the rack tending to hold the rack in normal position, means on the handle to engage the gear so that a downward movement of the handle will turn said gear to operate said rack, said gear and said means being arranged to be rendered inoperative when the fifth wheel member is turned so that the steering wheel is reversed, 45 a platform on said frame, lifting devices between the frame and the platform operable by longitudinal movement of the platform, all constructed and arranged so that said handle, gear, and rack may be manipulated to move the platform and thus actuate said lifting devices, a catch to hold said platform lifted, releasing means therefor, actuated by movement of the platform and controlled by the movement of the handle.

60 15. A lifting truck, comprising, a wheeled frame having a steering wheel swiveled at

the front end thereof to turn about a vertical axis passing through the horizontal axis of the wheel, a handle horizontally pivoted to said fifth wheel member in line with said vertical axis, a gear mounted to turn on said last-named horizontal axis, a rack slidably mounted for horizontal movement in said fifth wheel member with which said gear meshes, means to hold said rack in normal position on said fifth wheel member, said handle having a part connected therewith arranged to engage and turn said gear when the handle is swung downwardly, all constructed and arranged so that the handle 75 may be turned with the fifth wheel member and the parts connected therewith through an arc sufficient to reverse the steering wheel, whereby the up and down movement of the handle takes place without engaging said gear, a platform on the frame, lifting devices operable by movement of the platform, said platform being arranged to be moved and controlled by said rack.

16. A lifting truck, comprising, a frame 85 mounted on wheels, a platform, devices operable on longitudinal movement of the platform to lift the latter, a steering handle, mechanism operable thereby to actuate the platform to operate said devices, a releasable catch to hold the platform in lifted position, a trip device operable on upward movement of the platform to release said catch and means to render said trip device inoperative while the platform is being lifted and locked 95 and on continued upward movement of the platform beyond locking position, all constructed and arranged so that the handle must be lowered and again raised before the platform can be lowered.

100 17. A lifting truck comprising a wheeled frame, a platform, devices operable on longitudinal movement of the platform to lift the latter, a steering handle mechanism operable on a downward swing of the handle to move the platform to operate said devices to lift the platform, a releasable catch operable after the platform is lifted to a predetermined height to lock the platform against downward movement, a trip device operable 110 by upward movement of the platform to release said catch and means to render said trip device inoperative on continued upward movement of the platform beyond said predetermined height, said means arranged to 115 prevent lowering of the platform until the handle is raised and again lowered.
